UNITED STATES PATENT OFFICE.

SAMUEL STEPHEN MORTON, OF HARRISBURG, PENNSYLVANIA.

INTERMITTENT-GRIP DEVICE.

1,423,007.

Specification of Letters Patent.

Patented July 18, 1922.

Application filed September 25, 1920. Serial No. 412,739.

To all whom it may concern:

Be it known that I, SAMUEL S. MORTON, a citizen of the United States, residing at Harrisburg, in the county of Dauphin and 5 State of Pennsylvania, have invented certain new and useful Improvements in Intermittent-Grip Devices; and I do declare the following to be a full, clear, and exact description of the invention, such as will enable others skilled in the art to which it 10 pertains to make and use the same.

My invention relates to improvements in intermittent grip devices for driving shafts and the like in a step by step manner, and 15 the invention has more particular reference to a device of this character having an oscillating motion.

This application forms a continuation in part of my United States application, Serial 20 No. 323,709 filed Sept. 15, 1919.

One object of the invention is to provide an intermittent grip device which may be set quickly and easily for driving a shaft or the like in either direction, or set with 25 equal facility in a neutral position at which no driving of the shaft will take place, even though the device continues to oscillate.

In carrying out the above, a flexible friction band surrounds the drum or shaft to be 30 driven and an oscillating lever is connected to the ends of said band for alternately contracting and releasing the latter. Before the device will operate in this manner, however, the band must be initially contracted by 35 relatively canting the band and lever, and a further object is to provide yielding means for effecting this canting, without interfering with proper release of the band on the idle strokes of the lever.

A still further object is to provide a device of the class set forth in which the 40 flexible band is contracted by cam action and in which the strength with which the shaft is gripped, is increased as the resistance to turning increases, thereby positively warding against any slippage of the band on the shaft or drum.

Yet another object is to provide an intermittent grip device which will be comparatively simple and inexpensive, yet absolutely 45 positive in operation, and one in which little wear will occur.

With the foregoing and minor objects in view, the invention resides in the novel construction and arrangement of parts herein- 50 after described and claimed, the descriptive

matter being supplemented by the accompanying drawings.

Figure 1 is an elevation, partly in section, showing an intermittent grip device constructed in accordance with my invention. 60

Figure 2 is a horizontal sectional view cut principally on line 2—2 of Fig. 1, parts however being broken away and in section below this line. 65

Figure 3 is a vertical sectional view with parts in elevation, showing a different position of parts from that disclosed in Fig. 1.

Figure 3^a is a detail horizontal sectional view taken on line 3^a—3^a of Fig. 3. 70

Figure 4 is a vertical transverse section as viewed on line 4—4 of Fig. 1.

Figure 5 is a view in elevation showing a different form of construction from that disclosed in the preceding figures. 75

In the drawings above briefly described, the numeral 1 designates a shaft to be intermittently driven, said shaft having an enlarged portion 2 forming a drum. Surrounding the drum 2 is a linked friction band 3 80 and an oscillatory lever 4 extends from the drum and is operatively connected with the ends of the band 3.

The band 3 as shown, comprises three metal links 5, 6 and 7, the link 7 being positioned between the inner ends of the links 5 and 6 and pivoted thereto at 8. The inner sides of all of the links are curved for tight contact with the drum 2 and I provide means for loosely connecting the free ends 90 of the links 5 and 6 with each other and for fulcrumming the lever 4 to the band. In the present showing, the link 5 is provided with a pair of inwardly extending ears 9 and the link 6 is formed with a similar ear 95 10 loosely received between said ears 9. All of the ears 9 and 10 are slotted in a direction transverse to the axis of the drum 2 and for future reference I have given the slots of the ears 9 the reference numerals 100 9^a while 10^a refers to the slot of the ear 10.

These slots loosely receive a fulcrum pin 11 by means of which the oscillatory lever 4 is connected with the band 3. The inner end of this lever is provided with a T-head 12 105 whose center carries the fulcrum pin 11 and whose ends are provided with rollers 13 or other appropriate shoes which engage cam surfaces 14 on the outer terminals 15 of the links 5 and 6. The band 3 is normally 110

spread or opened to bring the shoes and cam surface into contact, by means of a coil spring or the like 16, the outer ends of the slots 9^a and 10^a, that is the ends adjacent the 5 free ends of the ears 9 and 10, then receiving the fulcrum pin 11 as shown in Figs. 1 and 2. With the parts in this position, the lever 4 may be oscillated without any turning effect whatever on the drum 2, since the 10 band 3 is loose on the latter and will turn to and fro with said lever. By relatively canting the band and lever, however in either direction, said band is initially contracted or tightened upon the drum so that 15 the frictional contact thus created, will cause the lever 4 to tilt on the fulcrum 11 during any subsequent movement. When the lever tilts in one direction on the fulcrum 11, the band 3 is tightened and there- 20 by rigidly grips and turns the drum 2, but during the return motion of the lever, the band is loosened to some extent and turns freely on the drum. By forcing the inner end of the lever in one direction, transversely 25 of the drum 2, the gripping device is set for rotating the drum clockwise, while forcing the end of the lever in the opposite direction will cause counter-clockwise rotation, and for the purpose of effecting this shift- 30 ing, I may provide any appropriate means, two examples being given below.

In the form of construction shown in Figs. 1, 2 and 3, the T-head 12 is provided with a laterally extending arm 20 having a 35 roller or other shoe 21 on its free end which is received in a curved guide 22 concentric with the drum 2, said guide being carried by the end of a spring arm 23 which is anchored at 24 to any suitable supporting 40 structure 25. Between its ends, the spring arm 23 carries a stirrup 26 receiving a cam 27 on a rock shaft 28 which may be turned at will by a suitable lever or the like 29. When the cam 27 is turned in one direction, 45 the spring 23 and the guide 22 are moved in the same direction, thereby shifting the T-head 12 transversely of the drum 2. When the cam is turned in the opposite direction, however, said T-head is moved 50 reversely. It will thus be seen that by properly actuating the lever 29, the grip device may be set for driving the drum 2 in either direction or for idling upon said drum.

55 In the form of construction shown in Fig. 5, the arm 20 is dispensed with and a yielding lever 30 is fulcrumed near one end to the cross head 12 of the lever 4, preferably upon the fulcrum pin 11 above described. At its 60 inner end, the lever 30 is provided with a fork or other appropriate bearing 31 which bears on the drum 2. Near the outer end of the lever 30, the lever 4 is provided with a series of teeth 32 into engagement with 65 which said lever 30 may be sprung. When

this lever is moved in one direction, the T-head 12 is shifted in the corresponding direction, while reverse movement of the head may be effected by shifting the lever 30 in the opposite direction. This lever may be 70 held in either of its extreme positions or at a neutral position by means of the teeth 32 and it will therefore be seen that by means of said lever, the device may be set for idling or for driving either forwardly or 75 rearwardly. Due to the resilient nature of the lever 30 and the spring 23, slight movement of the inner end of the lever 4, transversely of the drum 2, as said lever alternately contracts and releases the band 3, is 80 permitted and it will also be seen that the lever 4 is in no manner seriously resisted in its tilting upon the fulcrum pin 11.

As clearly shown in the several views, the T-head 12 is preferably constructed of two 85 metal plates secured to opposite sides of the lever 4 and the free ends of the links 5 and 6 are received between said plates for co-operation with the shoes 13. However, although this construction is preferred, it 90 need not be followed in all instances.

Regardless of the exact details disclosed, the operation of the device is as follows: As long as the T-head 12 is held in a neutral position by means of the arm 20 and associated parts, or the lever 30, the band 3 is loose upon the drum 2 as shown in Figs. 1 and 5 and hence said band will turn freely with any oscillation of the lever 4 and will produce no driving of the drum. The 100 moment that the band 3 and lever 4 are relatively canted, however, in either direction, driving of the drum takes place. In Fig. 3, the cam 27 has been operated, to cause the spring 23 and guide 22 to shift the 105 T-head 12 to the left. This movement pulls the fulcrum pin 11 into tight contact with the outer ends of the slots 9^a as shown in the detail sectional view, designated Fig. 3^a. At the same time, the left hand shoe 13 is 110 brought into contact with the adjacent cam surface 14, crowding the link 6 inwardly and contracting the entire band 3 upon the drum 2. When the lever 4 now moves to the right, it will turn slightly upon the fulcrum pin 11 since the band 3 is now frictionally gripping the drum 2. The moment 115 this turning of pin 11 takes place, the left-hand shoe 13 coacts with the cam surface 14 to crowd the link 6 into still tighter contact with the drum. During this action, the fulcrum pin 11 draws to the left on the free end of the link 5 and the latter is thus also 120 tightly held against the drum. The result is that no slippage whatever of the band 125 3 takes place and the drum 2 is positively turned in the direction of the arrow shown in Fig. 3. When the lever 4 moves on its return or idle stroke, that is to the left, the left-hand shoe 13 rides down the cam surface 130

14 with which it was previously in contact, thereby releasing the grip of the band 3 on the drum 2, with the result that said band returns to its initial position without 5 moving the drum in a retrograde direction. Whenever it is necessary to reverse the direction in which the drum 2 is driven, the cam 27 is operated to throw the spring 23 to the right. The same operation as that above 10 described then takes place, except that the right-hand shoe 13 and cam surface 14 come into play, and the fulcrum pin 11 pulls against the outer end of the slot 10^a. The device will therefore be operative when moving 15 in the direction in which it was previously idle, and vice versa.

The operation of the form of construction shown in Fig. 5 is identical with that above set forth, the only difference between the two 20 forms being in the manner of relatively canting the band 3 and the lever 4.

From the foregoing, taken in connection with the accompanying drawings, it will be seen that I have devised a comparatively 25 simple and inexpensive, yet a highly efficient and in every way desirable, intermittent grip device. This device is usable wherever a ratchet motion is necessary, for instance on the drum of a wire stretcher, in which 30 instance the form of construction as shown in Fig. 5 is preferably followed. Figs. 1, 2 and 3 illustrate the form of construction which is preferably followed when adapting 35 the invention to a transmission mechanism, for instance on a tractor. In these views, the numeral 25 represents a portion of a transmission casing in which all of the working parts may be located. When the invention is used in this connection, the 40 lever 4 is power driven, but this need not be entered into in detail in view of the fact that the present application is restricted to the intermittent grip device, regardless of its use.

45 Since numerous changes may be made without departing from the spirit of the invention, as claimed, it will of course be understood that the accompanying disclosure is for illustrative purposes only.

50 I claim:

1. In an intermittent grip device, a drum, a flexible band surrounding said drum, a band-contracting lever adapted to travel bodily along an arcuate path concentric with 55 said drum, and means for positively canting said lever, and band relatively before any travel of said lever along said arcuate path, whereby to initially contract said band.

2. In an intermittent grip device, a drum, 60 a flexible band surrounding said drum, a band-contracting lever adapted to travel bodily along an arcuate path concentric with said drum, and spring means acting on said lever for rocking the latter and positively 65 contracting said band upon the drum be-

fore any travel of said lever on said arcuate path.

3. In an intermittent grip device, a drum, a band surrounding said drum, a lever having one end positioned adjacent the ends of 70 the band, means loosely connecting said ends with each other and forming a fulcrum for said lever, and means on said lever engaging one of said ends and cooperable with the aforesaid fulcrum in contracting the 75 band on the drum when the lever is turned in one direction.

4. In an intermittent grip device, a drum, a band surrounding said drum, a lever having one end positioned adjacent the ends of 80 the band, means loosely connecting said ends with each other and forming a fulcrum for said lever, one of said ends having a cam surface, and a shoe carried by said lever at a point spaced from its fulcrum, said shoe 85 engaging said cam surface to crowd said one end inwardly and thereby contract the band, when the lever is turned in one direction.

5. In an intermittent grip device, a drum, an oscillatory lever having a T-head at one 90 end extending transversely of said shaft, a fulcrum pin at substantially the center of said T-head, shoes near the ends of said T-head, a band surrounding the drum with its ends provided with openings loosely receiving 95 said fulcrum pin, said ends having cams contacting with said shoes and acted on by the latter to contract the band for turning the drum in one direction or the other after said band has been initially contracted, and 100 means for relatively canting said lever and said band to initially contract the latter for driving in either direction.

6. In a transmission, a drum, a contractable band surrounding said drum, means 105 for turning said band alternately in opposite directions, for contracting said band around said drum when turning in one direction and for releasing said band when turning in the other direction, and means 110 under the control of the operator for positively contracting said band initially and for releasing said band independently of the band operating means.

7. In a transmission, a drum, a friction 115 band surrounding said drum, a floating lever to which the ends of said band are connected, means for moving said lever bodily in a to and fro manner, a shoe carried by said lever and located at a point spaced 120 laterally from its fulcrum, a curved track concentric with said drum and in contact with said shoe, and means for shifting said track toward and from said drum.

8. In a transmission, a drum, a friction 125 band surrounding said drum, a floating lever to which the ends of said band are connected, means for moving said lever bodily in a to and fro manner, a shoe carried by said lever and located at a point spaced 130

laterally from its fulcrum, a curved track concentric with said drum and in contact with said shoe, a spring connected to said track, and means for moving said spring to shift said track toward and from the drum.

9. In a transmission, a drum, a friction band surrounding said drum, a floating lever to which the ends of said band are connected, means for moving said lever bodily in a to and fro manner, a shoe carried by said lever and located at a point spaced

laterally from its fulcrum, a curved track concentric with said drum and in contact with said shoe, a spring arm carrying said track, said spring arm being mounted at one end of a fixed support, and a manually operable cam for moving said spring arm to shift said track either toward or from the drum.

In testimony whereof I have hereunto set my hand.

SAMUEL STEPHEN MORTON.
